UNITED STATES PATENT OFFICE.

HUGH FREDERICK MARRIOTT, OF LONDON, ENGLAND.

POINT AND SWITCH OPERATING APPARATUS.

No. 926,668.

Specification of Letters Patent.

Patented June 29, 1909.

Application filed February 15, 1909. Serial No. 477,899.

To all whom it may concern:

Be it known that I, HUGH FREDERICK MARRIOTT, a subject of the King of Great Britain and Ireland, residing at London, England, have invented a new and useful Improvement in Point and Switch Operating Apparatus, of which the following is a specification.

This invention relates to apparatus for use 10 in connection with railway or tramway points and switches whereby the said points and switches can be operated from a vehicle or train in motion on the rails.

In the accompanying drawings, Figure 1 is 15 a plan, Fig. 2 is a sectional side elevation taken on the line 2—2 of Fig. 1, and Fig. 3 is an end view of one construction of the switch-operating devices arranged on the track adjacent to a set of switch points to be 20 operated. Fig. 4 is a sectional side elevation of a portion of a vehicle provided with one construction of the actuating device for use in connection with the means for operating the switch, Fig. 5 is a front elevation 25 of the apparatus shown in Fig. 4 together with a portion of the apparatus shown in Figs. 1, 2 and 3, and Fig. 6 is a vertical section of a detail of the apparatus shown in Figs. 4 and 5.

Like letters indicate like parts throughout the drawings.

A A' are the rails of the main line, A' A' and A² A² are the rails of two sidings. a a and a' a' are the movable tongues of 35 switch points at the junction of the main rails A A and the siding rails A' A', A² A². The tongues a a and a' a' are connected together in pairs by tie rods a² and a³ respectively, and are each pivoted at a⁴ to base 40 plates a⁵.

B is a casing or framework, secured in position in any suitable way a short distance from the switch. In this framework B levers B' B² are pivoted at b' b² so as to be 45 capable of moving in a horizontal plane. At their rear ends the levers B' B² are each provided with downwardly extending portions B³ having slots b³. These slots are adapted to be engaged by pins c³ upon arms c' carried by rocking shafts C C' which also carry arms c⁵ c⁶ with pins c⁷ c⁸ that engage with slots a⁶ a⁷ in arms a⁸ a⁹ upon the tie rods a² a³. The said tie rods pass through holes in the arms a⁸ a⁹ which are secured in 55 the desired position upon the tie rods by nuts A¹⁰. Each of the rocking shafts C C' is

mounted at one end in a recess B⁵ in the framework B, and at its other end in a similar recess in a bearing C². Collars C³ upon the shafts C C' prevent longitudinal movement in one direction; longitudinal movement in the other direction is prevented by the bosses, c⁹ and c¹⁰ upon the arms c' c² and c⁵ c⁶ respectively. 60

The forward and rear ends of the casing B are provided with longitudinal guiding grooves B⁶ B⁷ B⁸. These grooves B⁶ B⁷ B⁸ are connected with each other by the passages or grooves b⁶, b⁷, b⁸ between the levers B' B² and between each of said levers and the adjacent side member B⁹ of the casing B. The lever B' is so constructed that it obstructs either the groove b⁶ or the groove b⁷, and the lever B² obstructs either the groove b⁷ or the groove b⁸. 70

D is a portion of the locomotive, tramcar, or other vehicle which is adapted to run with its running wheels D' D² upon the rails A A, A' A' or A² A². The actuating devices for the switch-operating device described above 80 is mounted upon the said vehicle and in the present instance includes a number of wheels E E' E² adapted to engage with the grooves B B' B⁸ and b⁶, b⁷, b⁸. The wheels E E' E² are each mounted upon a slide E³ (Fig. 6) 85 adapted to move vertically in a casing E⁴ secured to a cross bar D² of the vehicle. Each slide E³ is made hollow, with a vertical slot e³ in one side, through which slot a member E⁵ projects. This member E⁵ is screwed into a tapped recess in the casing E⁴, as at E⁶, and between each of the said members and the top of each slide E³ a spring E⁷ is arranged. These springs will tend to keep the wheels E E' E² in their raised position. Upon the 90 platform D³ plungers F F' F² are provided for controlling the wheels E E' E² respectively. The plungers are made hollow to receive springs f which form cushions between the hollow plungers and the heads F³ of pins F⁴. 95 The hollow plungers and the heads F³ slide in tubular casings F⁵ extending through the platform D³. The lower ends of the pins F⁴ extend through holes in a plate F⁶ secured to the underside of the platform D³, and are 100 provided with heads F⁷ which bear upon arms F⁸ of bell crank levers pivoted upon a pin F⁹ carried by brackets F¹⁰ formed upon the plate F⁶. The other arms F¹¹ of the bell crank levers have each one end of a Bowden 105 wire F¹² secured thereto, the other end of the wire F¹² secured thereto, the other end of the 110 said wire passing through a hole e⁴ extending

through the cross bar D^2 and the casing E^4 , thence through the slot e^3 , a hole or opening in the member E^5 and being finally secured to the slide E^3 at e^3 .

5. The apparatus shown in Figs. 1 to 3 is in position for a vehicle or train to travel along the lines $A A$. If it is desired to pass from the lines $A A$ to the lines $A' A'$, the plunger F is depressed to bring the wheel E into engagement with the groove B^6 from which it passes, as the vehicle travels forward, to the groove b^6 where it comes into contact with the lever B' and forces the same to the right, that is to say, into the position indicated by broken lines in Fig. 1. This movement of the lever B' is transmitted by the portion of the arm $c' c^6$ to the rocking shaft C from which movement is communicated to the points a by means of the arms $c^6 c^7$ and a^8 and the tie rod a^2 . Similarly, when it is desired to pass from the lines $A A$ to the lines $A^2 A^2$ the wheel E^2 is depressed by means of the plunger F^2 to operate the lever B^2 , the rocking shaft C' and the points $a' a'$. When either of the sidings has been opened by a vehicle, the next vehicle can of course, pass on to the said siding without actuating the points; if however the vehicle is desired to keep to the main line, the central wheel E' must be operated to clear the groove b^7 of whichever lever is obstructing it in order to close both sidings, and to bring the points to the position shown in full lines in Fig. 1 of the drawing.

35. It will be obvious that the construction illustrated and described may be easily modified to enable various numbers and points to be operated.

What I claim as my invention and desire 40 to secure by Letters Patent in the United States of America, is:—

1. In railway and tramway point and switch operating apparatus, the combination of a main track, a side track, movable points at the junction of the main and side tracks, tie bars connecting the said points, a slotted arm on the tie bar, a lever situated adjacent to the points, a rocking shaft adapted to be operated by the lever, a rocking arm 45 on the shaft, means upon the rocking arm for engaging with the slot in arm on the tie bar, a vehicle adapted to travel upon the main and side tracks, and means situated upon the vehicle and adapted to actuate the lever.

55. 2. In railway and tramway point and switch operating apparatus, the combination of a main track, a plurality of side tracks, movable points at the junction of the main and side tracks, tie bars connecting the pairs 60 of points, a slotted arm on each tie bar, a plurality of levers situated adjacent to the points, a plurality of rocking shafts each of which is adapted to be operated by one of the levers, rocking arms on the shafts, means 65 upon each rocking arm for engaging with the

slot in each arm of each tie bar, a vehicle adapted to travel upon the main and side tracks, and means situated upon the vehicle and adapted to operate the levers so as to rock the shaft that will open the desired side track.

3. In railway and tramway point and switch operating apparatus, the combination of a main track, a side track, movable points at the junction of the main and side tracks, tie bars connecting the said points, a slotted arm on the tie bar, a casing situated adjacent to the points, a lever pivoted in the casing, a rocking shaft adapted to be operated by the lever, a rocking arm on the shaft, a pin upon the rocking arm for engaging with the slot in the arm on the tie bar, a vehicle adapted to travel upon the main and side tracks, and means situated upon the vehicle and adapted to actuate the lever.

4. In railway and tramway point and switch operating apparatus, the combination of a main track, a plurality of side tracks, movable points at the junction of the main and side tracks, tie bars connecting the pairs 90 of points, a slotted arm on each tie bar, a casing situated adjacent to the points, a plurality of levers pivoted in the casing, a plurality of rocking shafts each of which is adapted to be operated by one of the levers, 95 means upon each rocking arm for engaging with the slot in each arm of each tie bar, a vehicle adapted to travel upon the main and side tracks, and means situated upon the vehicle and adapted to operate the levers so 100 as to rock the shaft that will open the desired side track.

5. In railway and tramway point and switch operating apparatus, the combination of a main track, a side track, movable points 105 at the junction of the main and side tracks, a casing situated adjacent to the points said casing being provided with two guiding grooves, a lever pivoted in the casing and adapted to obstruct either one or the other 110 of the guiding grooves in the casing, means whereby movements of the lever can be transmitted to the movable points, a vehicle adapted to travel upon the main and side tracks, and means situated upon the vehicle and adapted to engage with either of the 115 guiding grooves in the casing so as to operate the lever and thereby move the points to open or close the side track.

6. In railway and tramway point and switch operating apparatus, the combination of a main track, a plurality of side tracks, movable points at the junction of the main and side tracks, a casing situated adjacent to the points said casing being provided with a plurality of guiding grooves, a plurality of levers pivoted in the casing each 125 lever being adapted to obstruct either one or the other of adjacent guiding grooves, means whereby movements of the different levers 130

can be transmitted to the movable points of the different sidings, a vehicle adapted to travel upon the main and side tracks, and means situated upon the vehicle and adapted 5 to engage with any desired guiding groove in the casing so as to operate any lever that obstructs the groove and thereby move the points to open the desired side track.

7. In railway and tramway point and switch operating apparatus, the combination 10 of a main track, a side track, movable points at the junction of the main and side tracks, a casing situated adjacent to the points said casing being provided with two guiding 15 grooves, a lever pivoted in the casing and adapted to obstruct either one or the other of the guiding grooves in the casing, means whereby movements of the lever can be transmitted to the movable points, a vehicle 20 adapted to travel upon the main and side tracks, wheels mounted upon the vehicle, and means whereby the said wheels can be lowered into engagement with either of the guiding grooves in the casing so as to operate 25 the lever and thereby move the points to open or close the side track.

8. In railway and tramway point and switch operating apparatus, the combination 30 of a main track, a plurality of side tracks, movable points at the junction of the main and side tracks, a casing situated adjacent to the points said casing being provided with a plurality of guiding grooves, a plurality of 35 levers pivoted in the casing each lever being adapted to obstruct either one or the other of adjacent guiding grooves, means whereby movements of the different levers can be transmitted to the movable points of the different sidings, a vehicle adapted to travel 40 upon the main and side tracks, wheels mounted upon the vehicle, and means whereby the said wheels can be lowered into engagement with any desired guiding groove in the casing so as to operate any lever that 45 obstructs the groove and thereby move the points to open the desired side track.

9. In railway and tramway point and switch operating apparatus, the combination 50 of a main track, a side track, movable points at the junction of the main and side tracks, a casing situated adjacent to the points said casing being provided with two guiding

grooves, a lever pivoted in the casing and adapted to obstruct either one or the other of the guiding grooves in the casing, means 55 whereby movements of the lever can be transmitted to the movable points, a vehicle adapted to travel upon the main and side tracks, two vertically movable slides mounted upon the vehicle, a wheel carried by each 60 of the said slides, means for keeping the slides normally in their raised position, two plungers mounted upon the vehicle, means whereby upon the depression of one of the plungers the corresponding slide is depressed 65 whereby its wheel is lowered into engagement with one of the guiding grooves in the casing so as to operate the lever and thereby move the points to open or close the side track.

10. In railway and tramway point and switch operating apparatus, the combination 70 of a main track, a plurality of side tracks, movable points at the junction of the main and side tracks, a casing situated adjacent to the points said casing being provided with a plurality of guiding grooves, a plurality of 75 levers pivoted in the casing each lever being adapted to obstruct either one or the other of adjacent guiding grooves, means whereby movements of the different levers can be transmitted to the movable points of the different sidings, a vehicle adapted to travel 80 upon the main and side tracks, a plurality of vertically movable slides mounted upon the 85 vehicle, a wheel carried by each of the said slides, means for keeping the slides normally in their raised position, a plurality of plungers mounted upon the vehicle, means whereby upon the depression of one of the plungers 90 the corresponding slide is depressed whereby its wheel is lowered into engagement with one of the guiding grooves in the casing so as to operate the lever that obstructs the groove and thereby move the points to open the desired side track.

In testimony whereof I have hereunto set my hand and seal in the presence of two subscribing witnesses.
